UNITED STATES PATENT OFFICE.

SPENCER OTIS, OF BARRINGTON, ILLINOIS.

PHOTOGRAPHIC TRACK DETECTOR.

Application filed April 26, 1924. Serial No. 709,124.

This invention relates to means for ascertaining the physical condition of a structure of protracted dimension, such, for instance, as railroad track or the rails thereof, and proceeds upon the principle of traversing the track by a vehicle equipped with means for continuously photographing the track as the vehicle progresses, with the effect of developing a substantially continuous record of the condition thereof. The preferred method of accomplishing the result involves, as well, the use of the material of the photograph, for instance, the strip upon which the images are successively taken, as a measure of the track traversed, and, therefore, as a means for determining the location in the track, or distances from a selected point, of the respective pictures, so that if any picture shows a defect or condition of particular interest, it will be practicable to locate the actual place where the condition exists. The exposures will, of course, be timed in a manner to produce sharp images notwithstanding the movement of the vehicle bearing the photographic apparatus, and the actinized material preferably in the form of a strip, will, of course, be fed as the exposures are made, after the manner of motion picture photography, although not necessarily with such rapid periodicity as will develop the appearances of motion on the principle of persistence of vision.

In the accompanying drawings, in which two embodiments of the invention are shown by way of illustration—

Figure 1 is a front elevation of an automotive track vehicle upon which is mounted apparatus adapted to continuously photograph surfaces of the track rails, and particularly those surfaces thereof which are normally obscured from view of an inspector from a position above the track.

Figures 2 and 3 show, on an enlarged scale, in front and side elevation, a photographic unit which is employed for each rail in Figure 1.

Figure 4 represents a strip of sensitized film upon which successive images from the rails may be projected and which, by reason of its feed in the photographic apparatus and lineal distance calibrations marked thereon, will serve the additional purpose of recording the relative position or approximate position of every image photographed.

Figures 5 and 6 are views corresponding to

Figures 2 and 3, showing a somewhat different arrangement of photographic unit, according to which, instead of taking separate pictures of the respective sides of the rail, a composite picture will be taken showing both sides of the rail in their existent relation.

It is to be understood that any detail in the construction and operation of the photographic apparatus not herein specifically illustrated, may be embodied in accordance with known practice in the construction and operation of a motion picture apparatus, particularly as regards the operation of feeding the film and effecting intermittent exposures.

Referring to Figures 1, 2, and 3, 1 represents a truck or car equipped with track wheels 2 and any approved form of motive power 3 arranged to propel it along a railroad track. Supported on truck 1 through means of brackets 4 are photographic cameras 5 which are to be understood as embodying automatic and continuously operating exposure mechanism and concurrently actuated film feeding mechanism of some approved and well known type. An important feature of this photographic apparatus, according to the present invention, resides in the provision of means for positively actuating the film feed and exposure mechanism in definite relation to the distance traversed by the truck 1, as, for instance, by gearing an axle 6 of wheel 2 with a sprocket 7 on a shaft 8 which is in turn connected by bevel gearing 9 with the internal mechanism of the camera, and thus causing each image to bear the same relative position on the film which the track portion, recorded by such image, occupies in the length of the track.

In order that the cameras 5 may record conditions of those portions of the rails which are obstructed from view from above, mirrors 10 are supported on arms 11 in reflective relation between said obscured portions of the rail and the lens openings of the camera; and in order that these mirrors may be temporarily withdrawn from normal position, to avoid rail splices or other obstructions along the track, the arms 11 are pivoted at 12 and provided with crank arms 13 connected through rods 14 with crank arms 15 on the shaft 16 that may, if desired, extend entirely across the vehicle so as to govern mirrors at both

2
rails alike. Shaft 16 will be rotated in any particular way, as, for instance, by means of one or the other of the hand levers 17.

A specimen of the sensitized tape or film that will be used is shown in Figure 4, wherein the figures "0" "25" "50" "5280" on the strip represent feet indicative of the longitudinal dimension of the rails traversed, so that by introducing the film into the camera with that portion thereof presented toward the lens which corresponds with the portion of the track upon which the vehicle rests, the images will be properly spaced in relation to the portions of the rail traversed, and by taking the nearest reading to any particular image, the general location of the condition in the track which the image records can be determined and actual inspection and repair can be undertaken.

If desired a cyclometer 18 can be used in connection with the driving mechanism, as, for instance, by having its sprocket wheel 19 in mesh with the chain 20 that connects the shafts 6 and 8, and by reading this cyclometer it can be determined just how far the vehicle is from a starting point in the track, and film with appropriate calibrations can be introduced in replacing exhausted film.

According to Figures 5 and 6, images reflected by the mirrors 10^a, mounted on pivots 12^a by arms 11^a and under control of crank arms 13^a with connections 14, are received and directed by a second pair of mirrors 10^b to a reflecting prism 10^c, whence the two images of opposite sides of the rail both enter a camera 5^a where they are recorded simultaneously as a single image, showing both sides of the rail in their actual relation. In this instance, the single camera has its sprocket wheel 7^a driven by a chain 20^a from the axle 6, and said chain is made to pass over the pinion 19 of cyclometer 18, as already described in connection with Figures 1 to 3.

In both the form of Figures 1 to 3 and that shown in Figures 5 and 6, light sources that will be employed in such relation to the surfaces to be photographed as will insure

ample illumination thereof; and these light sources are preferably mounted on the same bracket arms 11 or 11^a with the mirrors 10, 10^a.

Inasmuch as the subject-matter of the present invention is applicable to uses other than roads equipped with guiding rails, for instance, an ordinary highway used by wheeled vehicles in general, or any surface requiring examination or running parallel with structures that need inspection, the terms "track", "rail", "railway" etc., as herein used, except when the context otherwise determines, are to be taken as typifying any road, way, or surface over which the photographically equipped vehicle may travel. 65

I claim:

1. In combination, a vehicle, photographic apparatus mounted upon said vehicle constructed to photographically record the physical condition of the rail upon which the vehicle travels, and reflecting means mounted on said vehicle in position to direct into the camera images of a selected portion of the rail to be photographed. 70

2. In apparatus for photographically recording the physical condition of railroad rails, a vehicle adapted to travel in a direction paralleling the rail, a reflector mounted upon said vehicle in position to reflect an image of an under portion of said rail, and photographic means in position to receive the image so reflected. 75

3. In apparatus for photographically recording the physical condition of the under surfaces of railroad rails, a vehicle adapted to travel a course parallel with the rail to be photographed, a system of mirrors mounted on said vehicle in position to reflect images from the under surfaces of both sides of said rail and project said images in parallel relation as a composite image, and photographic apparatus mounted on said vehicle in position to receive the composite image thus projected. 80

Signed at Chicago, Illinois, this 21st day of April, 1924. 85

SPENCER OTIS.
